UNITED STATES PATENT OFFICE.

EDMOND VAILLE AND HENRI BOSC, OF MARSEILLE, FRANCE.

TUBE-FILLING DEVICE.

1,412,150.

Specification of Letters Patent. Patented Apr. 11, 1922.

Application filed August 10, 1920. Serial No. 402,716.

To all whom it may concern:

Be it known that we, EDMOND VAILLE and HENRI Bosc, citizens of the Republic of France, residing at Marseille, in the Republic of France, have invented new and useful Improvements in Tube-Filling Devices, of which the following is a specification.

This invention relates to a device for filling tubes, the object of the invention being 10 to provide an improved device by which chemists and others are enabled quickly to fill tubes with pharmaceutical products, such as creams or ointments.

A further object of the invention is to provide a device of the character set forth which is extremely simple in construction and economical to manufacture.

With the foregoing and other objects in view, the invention consists in the novel features of construction and combination of parts which will be more fully described hereinafter and particularly pointed out in the claims.

In the drawings accompanying and forming part of this specification,

Fig. 1 is a side elevation of a tube, illustrating the manner in which the device is used in connection therewith;

Fig. 2 is a side elevation taken at right angles to Fig. 1;

Fig. 3 is an end view of Fig. 1;

Fig. 4 is a plan view of one of the channel members of the device;

Fig. 5 is a plan view of the other channel member;

Fig. 6 is a transverse sectional view taken on the line 6—6 of Fig. 4; and

Fig. 7 is a transverse section taken on the line 7—7 of Fig. 5.

40 The same characters of reference designate the same parts in the different figures of the drawing.

Referring to the drawing, E designates a tube such as is commonly used by chemists 45 and others for the reception of creams, ointments, etc. The improved filling device consists of a pair of channel members A and B, of semi-circular form in cross section. The member A is somewhat longer than the tube 50 with which it is intended to be used, and is of such diameter that it fits snugly within said tube. This member A is entirely open at both ends thereof, and is provided at one end with a lug D extending at right angles 55 therefrom at its periphery, for permitting the withdrawal of the member A from the tube E after the latter has been filled.

The other member B of the filling device is of approximately the same length as the tube with which it is intended to be used, 60 and is of a diameter sufficiently large to permit it to snugly fit the exterior of said tube. This member B is provided at one end thereof with an internal disk C which is adapted to form a piston within the member 65 A when the device is in use in the manner hereinafter described.

The operation of the device is as follows: The substance to be introduced into the tube E is first deposited in the member A, this 70 member is then inserted within the tube E as far as it will go. The member B is then placed on the exterior of the tube E in diametrically opposite relation to the member A. Thereupon the member B is slid along 75 the tube E so that its disk piston C engages the material within the member A and forces it up into the tube E, the sliding movement of B being continued until the disk C is in engagement with the end of the tube, where- 80 upon the operator will hold it in this position while he withdraws the member A by taking hold of its lug D and sliding it out of the tube. Upon then removing the member B from the tube, the latter can be closed 85 at the bottom in the usual manner.

Having thus described our invention, what we claim is:

1. A tube filling device, comprising a pair of semi-tubular members, one adapted to fit 90 within and the other without the tube to be filled, one of said members being slidable relatively to the tube and to its companion member and having piston means adapted to operate within said companion member dur- 95 ing such sliding movement.

2. A tube-filling device, comprising a pair of members one adapted to fit within and the other without the tube to be filled, one of said members being longer than the other 100 and having its ends open, the shorter member being adapted to slide relatively to the tube and to said longer member and having a piston disk adapted to pass into said longer member through one of its ends during said 105 sliding movement.

In testimony whereof we have signed our names to this specification.

EDMOND VAILLE.
HENRI BOSC.
